UNITED STATES PATENT OFFICE

THOMAS T. MABBITT, OF SACRAMENTO, CALIFORNIA

DESIGN FOR A DISPENSING STAND

Application filed January 25, 1929. Serial No. 29,766. Term of patent 3½ years.

To all whom it may concern:

Be it known that I, THOMAS T. MABBITT, a citizen of the United States, residing at Sacramento, in the county of Sacramento and State of California, have invented a certain new, original, and ornamental Design for a Dispensing Stand, of which the following is a specification, reference being had to the accompanying drawing, forming part thereof, and in which the figure is a perspective view of a dispensing stand, showing my new design.

I claim:

The ornamental design for a dispensing stand, as shown.

THOMAS T. MABBITT.
